WATER CLOSET BOWL

Burton Harvey, Mansfield, Ohio, assignor to Borg-Warner Corporation, Chicago, Ill.

Filed May 15, 1970, Ser. No. 23,023

Term of patent 14 years

Int. Cl. D23—02

U.S. Cl. D23—67

FIG. 1 is a perspective view of a water closet bowl showing my new design;

FIG. 2 is a side elevational view thereof;

FIG. 3 is a front elevational view thereof;

FIG. 4 is a top plan view thereof; and

FIG. 5 is a rear view thereof.

The broken line representation of a water closet tank in FIG. 1 is for the purpose of illustration only.

I claim:

The ornamental design for a water closet bowl, substantially as shown and described.
